UNITED STATES PATENT OFFICE.

CHARLES F. KETTERING, OF DAYTON, OHIO, ASSIGNOR, BY MESNE ASSIGNMENTS, TO
DELCO-LIGHT COMPANY, OF DAYTON, OHIO, A CORPORATION OF DELAWARE.

AUTOMATIC SWITCH.

Application filed October 21, 1919. Serial No. 332,287.

To all whom it may concern:

Be it known that I, CHARLES F. KETTERING, a citizen of the United States of America, residing at Dayton, county of Montgomery, State of Ohio, have invented certain new and useful Improvements in Automatic Switches, of which the following is a full, clear, and exact description.

This invention relates to switches and 10 more particularly to automatic switches which are actuated mechanically by instrumentalities which are used for measuring the work being performed.

One of the objects of the present invention is to provide an automatic switch adapted to be attached to a meter, herein shown as an ampere hour meter, having provisions for quickly breaking the switch contacts thereby preventing pitting and 20 burning of the contacts.

Other and further objects of the present invention will be apparent from the following description, reference being had to the accompanying drawings, wherein a preferred embodiment of one form of the present invention is clearly shown.

In the drawings:

Fig. 1 is a front elevation of an ampere-hour meter dial showing the contacts closed;

30 Fig. 2 is a side elevation of Fig. 1;

Fig. 3 is a front elevation showing the contacts broken;

Fig. 4 is a side elevation of Fig. 3;

Fig. 5 is a front elevation showing the 35 contacts closed and also showing the position of the breaking elements while the batteries are being discharged;

Fig. 6 is a side elevation of Fig. 5; and

40 Fig. 7 is a side elevation showing the method in which the contacts are slowly separated.

Referring to the drawings, there is shown a dial 121 particularly applicable to an ampere-hour meter of the usual construction, 45 which rotates an indicating hand in a certain direction when the current being measured flows in a certain direction, and rotates the hand in the opposite direction when the meter measures current flowing in 50 the opposite direction. A contact 122 is carried on the face of the dial 121 and held in place by rivets 123. Contact 122 is insulated from the dial 121 by insulating blocks 124 and 125. Adjacent to the dial 55 121 is a plate 126 provided at one side with

a terminal 127, this terminal being insulated from the plate 126 by insulating blocks 128 and 129. Terminal 127 is connected to contact 122 by a bus bar 130. Bus bar 130 is connected to contact 122 by means of the 60 rivets 123. Said rivets are also used for conducting the current from the bus bar 130 through the insulating blocks 124 and 125 to contact 122. Contact 122 is provided with an inclined surface 131, as is clearly 65 shown in Figs. 2, 4, 6 and 7. A terminal 132 is connected at the other side of the plate 126 and with resilient contact 133 which is normally in contact with contact 122. Resilient contact 133 is provided with 70 an inclined beveled edge portion 134 and this portion 134 is at such an angle that when force is applied thereto, the contact 133 will tend to move away from the contact 122. 75

Mounted in the center of the meter is a hand 135 which is adapted to travel over the face of the dial 121. Said hand is provided with the resilient member 136 which will tend to travel with the hand over the inclined surface 131 of the contact 122. 80

Current flowing in a certain direction through the meter will cause the hand 135 to travel over the face of the dial in a clockwise direction and the resilient member 136 85 attached to the hand will slide upwardly on the inclined surface 131 of contact 122, storing energy into the resilient member. When the hand 135 has moved a predetermined distance said resilient member 136 90 will drop off of the inclined surface onto the resilient contact 133, thereby separating contact 133 from contact 122. When current flows through the meter in the opposite direction the hand 135 will move in a 95 counter-clockwise direction across the dial 121. The resilient member 136 will pass underneath the inclined surface 131 of contact 122 as shown in Figs. 5 and 6 because of its tendency to separate itself from the hand 100 135.

The present invention is particularly applicable to meters used in battery-charging systems including an internal-combustion engine, a dynamo driven thereby, and a controller for maintaining the circuit connections between the battery and dynamo and ignition for the engine, while the dynamo is operative. The quick operating switch 105 may be used for controlling the ignition cir- 110

cuit of the engine to stop the engine after a certain amount of current has passed through the meter, whereby the dynamo is rendered inoperative and the circuit between the battery and dynamo and the ignition circuit is rendered inoperative at the controller. Current flowing from the battery to a work circuit of the battery-charging system will cause the hand to rotate counter-clockwise and the contact 133 will re-engage contact 122.

Should the desire be to start the engine when the resilient member is in the position in which the resilient member 136 is underneath the contact 122, as shown in Fig. 5 and Fig. 6, the quick breaking mechanism herein described will not be in a position to operate because of the incapability of the resilient member to slide upwardly on the inclined surface 131. However, the hand 135 is still capable of breaking the ignition circuit again when the battery has been charged a predetermined amount. Now as the meter measures current flowing into the battery, the hand 135 will again travel in a clockwise direction and will come in contact with inclined edge portion 134 of the resilient member 133 pushing said resilient member down and away from contact 122. In this manner the ignition circuit will be broken again and the engine will cease to operate.

It can be seen from the foregoing description that certain advantages are present. For instance the burning and arcing of the switch contacts is prevented by quickly breaking the contacts in the manner described. In case the quick action mechanism is in such a position that it cannot operate, means are provided for separating these contacts at all events. As circumstances will seldom arise which might prevent the quick action mechanism from operating, it is immaterial that occasionally a quick break is not obtained.

While the form of mechanism herein shown and described constitutes a preferred embodiment of one form of the invention, it is to be understood that other forms might be adopted and various changes and alterations made in the shape, size and proportion of the elements therein without departing from the spirit and scope of the invention.

What I claim is as follows:—

1. A device of the kind described comprising the combination of an automatic switch, having cooperating contacts; of a meter; of a mechanism operated by the meter, said mechanism including a movable resilient member; and means provided in the path of movement of said resilient member for causing energy to be stored therein as the member is moving, and for permitting said resilient member to be released and to suddenly strike against one of said contacts

thereby obtaining a quick actuation of said contacts.

2. A device of the kind described comprising the combination of an automatic switch, having cooperating contacts; of a meter; of a mechanism operated by the meter, said mechanism including a movable resilient member; of a part having an inclined surface projecting in the path of movement of said resilient member for causing said member to be flexed as said member moves over said inclined surface and then for permitting said resilient member to be released and to suddenly strike against one of said contacts thereby obtaining a quick actuation of said contacts.

3. In a device of the kind described, the combination with cooperating contacts; of a meter operable in two directions to indicate the inflow or outflow of quantities to be measured; of a normally unbent resilient member actuated by said meter; and a part provided with an inclined surface mounted in the path of movement of the resilient member for causing flexing of the resilient member to store energy therein as the meter moves in one direction, whereby when the resilient member is suddenly released upon moving away from the inclined surface the switch contacts will be suddenly separated, said part having provisions permitting the resilient member moving away from the switch when the meter moves in the opposite direction and for causing said member to be restored to a position whereby said member may again engage the inclined surface when the meter again moves in the first mentioned direction.

4. In a device of the kind described, the combination with cooperating contacts; of a meter operable in two directions to indicate the inflow and outflow of quantities to be measured; of a movable resilient member actuated by said meter; and a part having an inclined surface projecting in the path of movement of said resilient member for causing energy to be stored therein as the member is moving in one direction and for permitting said resilient member to be released and to suddenly strike against one of said contacts thereby obtaining a quick break of said contacts, and for permitting the movement of the resilient member in an opposite direction allowing the contacts to come together and, after a predetermined movement of said resilient member in the said opposite direction, to permit said member to be restored to the normal position for engagement by said inclined surface.

5. In a device of the kind described, the combination with cooperating contacts; of a meter operable in two directions to indicate the inflow and outflow of quantities to be measured; of a movable resilient member actuated by said meter; of a part having an

inclined surface projecting in the path of movement of said resilient member for causing energy to be stored therein as the member is moving in one direction and for permitting said resilient member to be released and to suddenly strike against one of said contacts thereby obtaining a quick break of said contacts, and for permitting the movement of the resilient member in an opposite direction allowing the contacts to come together and, after a predetermined movement of said resilient member in the said opposite direction, to permit said member to be restored to the normal position for engagement by said inclined surface; and provisions for separating the contacts by movement of the meter in the first mentioned direction in case the said predetermined movement in said opposite direction has not taken place.

6. A device of the kind described comprising the combination of an automatic switch having cooperating contacts; of a movable mechanism including a resilient member; and means provided in the path of movement of said resilient member for causing energy to be stored therein as the member is moving, and for permitting said resilient member to be released and to suddenly strike against one of said contacts thereby obtaining a quick break of said contacts.

7. A device of the kind described comprising the combination of an automatic switch having cooperating contacts; of a movable mechanism including a resilient member, said mechanism being movable in two directions; and means provided in the path of movement of said resilient member for causing energy to be stored therein as the member is moving in one direction and for permitting said resilient member to be released and to suddenly strike against one of said contacts, and for permitting the movement of the resilient member in the other direction allowing the contacts to come together and, after a predetermined movement of said resilient member in the said other direction, to permit said member to be restored to the normal position for engagement with said means.

8. A device of the kind described comprising the combination of an automatic switch having cooperating contacts; of a movable mechanism operable in two directions, said mechanism including means for obtaining a quick separation of the contacts while said mechanism is moving in one direction, said mechanism including means for restoring the contacts to normal conditions for repetition of the quick separating operation by a certain movement of the mechanism in the other direction; and means provided for obtaining a separation of said contacts by a movement of the mechanism in the first named direction, said means being

operative in case the mechanism has not moved sufficiently in said other direction to permit the quick separating mechanism to become operable.

9. A device of the kind described comprising the combination of an automatic switch having cooperating contacts; of a movable mechanism operable in two directions, said mechanism including means for obtaining a quick actuation of the contacts while said mechanism is moving in one direction, said mechanism including means for restoring the contacts to normal condition and for conditioning the quick actuating means for repetition of the quick actuating operation by a certain movement of the mechanism in the other direction; and auxiliary means provided for obtaining an actuation of the contacts by a movement of the mechanism in the first named direction, said means being operative in case the mechanism has not moved sufficiently in said other direction to condition the quick operating mechanism.

10. A device of the kind described comprising the combination of an automatic switch having cooperating contacts; of a movable mechanism operable in two directions, said mechanism including means for obtaining a quick actuation of the contacts while said mechanism is moving in one direction, said mechanism including means for restoring the contacts to normal condition and for conditioning the quick actuating means for repetition of the quick actuating operation by a certain movement of the mechanism in the other direction; and an indicator hand actuated by the mechanism, said hand and one of said contacts having provisions for actuating the contacts by a movement of the mechanism in the first named direction and operative in case the mechanism has not moved sufficiently in said other direction to condition the quick operating mechanism.

11. A meter comprising, in combination, a dial, cooperating switch contacts adapted to be actuated for opening and closing a circuit, and means operated by the meter for effecting a quick actuation of said contacts, said means including a resilient member movable transverse to the face of said dial to actuate one of said contacts.

12. A meter comprising, in combination, a dial, cooperating switch contacts adapted to be actuated for opening and closing a circuit, and means operated by the meter for effecting a quick actuation of said contacts, said means including a member movable transverse to the face of the dial to actuate one of said contacts.

13. An electric meter comprising in combination, a movable mechanism, a resilient member adapted to be actuated by the mechanism, said member being adapted to be

flexed to store energy therein, and then be suddenly released by operation of the mechanism, and a movable switch contact adapted to be actuated by the resilient member when the member is suddenly released whereby said contact is quickly actuated.

14. An electric meter comprising, in combination, a movable mechanism including a shaft, an indicator hand carried by the shaft, a resilient member adapted to be ac-

tuated by the shaft and adapted to actuate the movable contact, said member being adapted to be flexed to store energy therein and be suddenly released by operation of the shaft, and a movable switch contact adapted to be actuated by the resilient member when the member is suddenly released whereby said contact is quickly actuated.

In testimony whereof I affix my signature,

CHARLES F. KETTERING.
